NONREFILLABLE BOTTLE

Hans Kanz, Zurich, Switzerland

Application March 21, 1933, Serial No. 661,894
In Switzerland March 28, 1932

3 Claims. (Cl. 215—21)

The present invention relates to improvements in bottles, jars or the like and in stoppers therefor and more especially to bottles for wines and spirits.

5 The main objects of the invention is to provide means to prevent and to detect re-filling or the illicit tampering with the closure of the bottle.

I attain this and other objects by means of a stopper adapted to be inserted in the normally 10 shaped neck of any bottle of usual design.

In the accompanying drawing forming part of this specification

Fig. 1 is a vertical sectional view of the bottle neck with the stopper inserted,

15 Figs. 2 and 3 are cross sections on the lines I—I and II—II respectively.

The stopper shown comprises a tubular body 1 of sheet metal. Within the tubular body 1 a second tube 2 is co-axially arranged, the parts 1 20 and 2 are rigidly connected with each other. The tube 2 is divided in two chambers 17, 18 by means of a disk 3 rigidly fixed in said tube 2. In the walls of the chambers 17, 18 slots 4 and 5 respectively are provided, the slots 4, 5 are circumferentially displaced with reference to each other to prevent a piece of wire or the like passed through one of the slots 4 to reach a slot 5 and to operate the valve body 11 or to retain it on the seat 10. The upper portion 6 of the tubular body 1 is screw-threaded, a screw-threaded cap 7 closes the upper orifice of the tube 2. Within the cap 7 a washer 8 of cork or other suitable material is arranged. The lower portion of the tubular body 1 is strengthened by a socket 9 of sheet metal which socket 9 provides a seat 10 for a ball 11. The ball 11 forming the valve body consists of a material the specific weight of which differs but little from that of the liquid which the bottle is to receive. Moreover a material is to 30 be used having the required hardness and which will not corrode etc. by the liquid. Amber and certain artificial compounds such as artificial resins have been found suitable. The ball 11 runs easily in the tube 2, a neck 12 pressed in said tube 2 acts as a stop for said ball 11 when the bottle is tilted and emptied. The tubular body 1 moreover is provided with a neck 13 which contacting with the tube 2 directs any liquid filled in at the mouth of the tube 2 into the chamber 18.

40 On the tubular body 1 a sleeve 14 of cork, rubber or the like, is arranged by which the stopper is tightly held in the neck 15 of the bottle. Over the neck 15 and the stopper-sleeve 14 a capsule 16 of tin foil etc. is tightly drawn which capsule 50 would be hurt by any attempt to remove the

stopper from the bottle neck. Any other suitable seal might be used.

The device operates as follows:

By pouring out the original contents of the bottle by unscrewing cap 7 and tilting the latter 5 the ball 11 runs down in the tube until it reaches the neck 12. The liquid passes through the stopper by the way indicated by the arrow III. The liquid passes through chamber 18, slots 5 into the space 19 between the parts 1 and 2 and enters 10 chamber 16 by the slots 4, and leaves the tube 2. A re-filling of the bottle is prevented by the ball 11 which comes to rest on the seat 10, by its own 15 weight and closes thereby the passage for the liquid. The re-filling of the bottle by using vacuum is also impossible. If the bottle is evacuated and if the bottle is immersed in the liquid with the stopper lowermost then the liquid will take the path indicated by the arrow IV. The liquid passes through tube 2, slots 4, into space 19, 20 slots 5 into the chamber 18. The liquid presses the ball 11 on the seat 10, as the ball 11 is of comparatively light material. The ball 11 prevents the liquid entering the bottle.

The new closure fulfills all the following requirements:

1. The stopper can be used with any normal and cheaply produced bottle which has not to be altered,

2. The mounting of the device is simple and 30 needs little time.

3. The purchase price of the stopper is low and the construction is very simple.

4. The bottle is non-refillable even when vacuum is used.

5. The stopper does not hinder a rapid dispensing of the liquid.

6. The valve is not accessible from the outside and cannot be tampered with by any means.

7. The bottle may be tightly closed by simple means the closure or seal may be opened without destroying parts thereof.

8. No essential part of the stopper can be removed without hurting the seal or capsule.

9. All the parts are simple and effective in 45 working.

10. After removing the stopper the bottle is ready to be used again.

I claim and desire to secure by United States Letters Patent:—

1. A closure for a non-refillable bottle comprising a stopper removably arranged in the neck of the bottle consisting of two concentrically arranged cylindrical members, forming at their connecting lower ends a seat for a valve, the inner 50 55

- member being divided in two chambers by a partition, both of these members being provided with beadings for guiding the liquid and the displacement of the valve.
- 5 2. A closure for a non-refillable bottle comprising a stopper removably arranged in the neck of the bottle consisting of two concentrically arranged cylindrical members, forming at their connecting lower ends a seat for a valve, the inner member being divided in two chambers by a partition, both of these members being provided with beadings for guiding the liquid and the movement of the valve, the beading of the inner member serving as a stop for the valve displacement.
- 10 3. A closure for a non-refillable bottle comprising a stopper removably arranged in the neck of the bottle consisting of two concentrically arranged cylindrical members, forming at their connecting lower ends a seat for a valve, the inner member being divided in two chambers by a partition, both of these members being provided with beadings for guiding the liquid and the displacement of the valve, the latter having about the same specific weight as the liquid. 5

HANS KANZ.
